[57] **CLAIM**

The ornamental design for a chair, substantially as shown and described.

DESCRIPTION

FIG. 1 is a perspective view of a chair showing my new design;

FIG. 2 is a side elevational view of one side thereof the other side elevation being essentially identical;

FIG. 3 is a front elevational view thereof;

FIG. 4 is a top plan view thereof;

FIG. 5 is a perspective view of a second embodiment of my design which differs from the first embodiment of FIG. 1 by the omission of the top cross-piece on the back-rest portion;

FIG. 6 is a perspective view of a third embodiment of my design which differs from the second embodiment of FIG. 2 by the addition of armrest portions; and

FIG. 7 is a side elevational view of the embodiment of FIG. 6.
